UNITED STATES PATENT OFFICE.

CHANDOS ROY DIMM, OF MUNCY, PENNSYLVANIA, ASSIGNOR TO ROBINSON MANUFACTURING COMPANY, OF MUNCY, PENNSYLVANIA, A CORPORATION OF PENNSYLVANIA.

CLEANER FOR SIFTING SCREENS.

Application filed March 26, 1925. Serial No. 18,490.

To all whom it may concern:

Be it known that I, CHANDOS R. DIMM, a citizen of the United States, residing at Muncy, in the county of Lycoming and State of Pennsylvania, have invented new and useful Improvements in Cleaners for Sifting Screens, of which the following is a specification.

This invention relates to cleaners for sifting screens adapted to be used in connection with various sifting mechanisms and of that type disclosed by Patent No. 218,530, dated August 12, 1879, and the purpose of the present improvement is to provide a simple and effective jarring or agitating means for a sifting screen which will prevent the meshes of the latter from clogging or filling with the material passing thereover during the sifting operation.

Previous to the present invention, and as disclosed in the patent above noted, loose balls have been arranged upon the upper surface of a screen-like or reticulated bottom of suitable mesh and confined in compartments for vibratory impact with relation to the screen above, to thereby jar the said upper screen and dislodge any material which might adhere to the same or clog its meshes. Balls and other loose devices have been adopted as the mediums for maintaining the screens in a cleanly condition or free from clogging.

The main object of the present invention is to improve the general organization of elements or components comprised in means for cleaning a sifting screen by not only arranging a plurality of resilient balls on the underside of the screen and on an open or perforated supporting surface, but to include transversely extending projecting means on the said perforated supporting surface that will render the balls more effective and quicker in their bounding action relatively to the sifting screen above the same, and thus insure the maintenance of the meshes of the sifting screen in a free or fully open or unclogged condition.

A further object of the present invention is to improve the general structure and organization of cleaning means for a sifting screen that will render the same strong and durable and comparatively simple in the assemblage of the several parts as well as

more effective in the desired function thereof.

With the foregoing and other objects and advantages in view, the invention consists in the construction and arrangement of the several parts which will be more fully herein-after described and claimed.

In the drawing:

Fig. 1 is a top plan view of a cleaning attachment embodying the features of the invention, showing a portion of the sifting screen thereover.

Fig. 2 is a longitudinal vertical section of the improved screen and cleaning attachment therefor.

Fig. 3 is a transverse vertical section of the same.

Fig. 4 is a detail perspective view of a portion of the improved device, showing the sifting screen removed and the movable cleaning devices withdrawn.

The numeral 5 designates a frame comprising side and end bars 6 and 7 of any suitable length or dimensions and of such vertical extent as to render the improved cleaning organization effective in the performance of its function. At regular intervals, or in predetermined spaced relation, transverse partitions 8 are interposed between and secured to the side bars or frame members 6, these partitions having opposite parallel sides and extending upwardly nearly the full extent or depth of the said side bars or frame members. The upper end edges of the partitions 8 are reduced or reversely beveled in an upward direction to form reduced terminal edges 9. On the top edges of the side and end bars or frame members 6 and 7 a sifting screen 10 of any suitable mesh, or which may vary in mesh, is secured, and to the bottom edges of the side and end bars or frame members 6 and 7 a supporting surface 11 is also secured, the said supporting surface 11 being of a reticulated character but coarser in mesh than the sifting screen 10 above, so that the material passing through the said latter screen may easily pass through the said supporting surface. The openings in the reticulated supporting surface 11 should be large enough to permit the free passage of the material sifted through the screen meshes 10.

Extending transversely across the im-

proved device between the side or frame bars 6 and in close contact with the lower reticulated supporting surface 11 are wire rods 12, which may be of any suitable dimensions but are preferably of about the diameter of heavy telephone wire, or approximately one-eighth of an inch in diameter. These rods 12 are disposed at regular distances apart between the partitions 8 and 10 also between the opposed end partitions of the series of the latter, and the end or frame bars 7. The rods 12 project above the upper surface of the reticulated supporting bottom or screen 11, and said rods are preferably circular in cross section. It will be seen that the partitions together with the upper screen 10 and lower reticulated supporting surface 11 conjointly with the side and end bars or frame members 6 and 7 provide a series of pockets 13, which are preferably of the same dimensions, and in these pockets 13 movable devices, preferably in the form of rubber balls 14, are mounted for free movement, or so that they will have an unrestricted bounding action, produced by the oscillation of the screen 10 and the remaining parts of the improved device including the reticulated supporting surface or bottom covering 11. It will also be seen that the upper reduced edges 9 of the partitions 8 are slightly below and out of contact with relation to the sifting screen 10. This latter arrangement permits the sifting screen to be free for vibration without coming in contact with blunt edges, and by this means the said screen is more sensitive to vibration through the bounding action of the movable cleaning devices or balls 14.

The operation of the improved screen cleaning device is very simple. When the sifting screen 10 together with the bars or frame members 6 and 7, partitions 8; lower reticulated supporting surface 11 and rods 12, are oscillated or vibrated as a unit, the balls 14 are caused to bound with considerable force against the upper sifting screen 10, and the bounding action or operation of these balls is rendered more effective and quicker by striking the rods 12, which divert the said balls in their bounding action and cause them to contact with various portions of the surface of the screen 10 over the several pockets. In other words, the balls 14 are given a greater activity in various directions, and their bounding action is, as a matter of course, induced by the reticulated supporting surface or lower screen 11 of coarse mesh to some extent, but the greater bounding force of the said balls is effected through their contact with the rods 12. The balls 14 are free to move over the rods 12 between their partitions 8 and the end members 7 and side members 6 of the frame, or the said balls during their operation traverse different parts of the compartments in a

very lively manner and are thrown up by engagement with the projecting portions of the rods 12 and strike the upper screen 10, as hereinbefore indicated. As shown in the accompanying drawing, there will be at least 70 two balls in each pocket 13, but the number of balls in the several pockets, however, may be modified as found necessary and in accordance with the general dimensions of the improved device. It will also be understood 75 that the balls are caused to be further diverted by engaging those portions of the side and end bars or frame members 6 and 7 exposed to the balls in the several pockets, and the balls will also strike or contact with 80 the straight sides of the partitions 8, and hence will be rendered extraordinarily effective in performing their cleaning function relatively to the screen 10.

The wire rods or projections 12, which are 85 circular in cross section and rest in close contact with the lower reticulated or screen-supporting surface 11 and extend continuously across the full width of the said supporting surface, cause the balls to bound or jump upwardly at different points lengthwise of the said cross rods or wires, and by this means an effective auxiliary for operating the balls is provided which will cause the balls to have a bounding action at various locations within the compartments. Heretofore, in comparatively coarse mesh or reticulated supporting surfaces, it has been found that the balls dropping into the meshes of the said supporting surface are 90 more or less restricted in their freedom of action by the resistance primarily set up by engagement of the balls with the meshes, and under this old structure the balls in their initial movement did not have sufficient momentum, or were not advantageously active, when rising out of the coarse screen-supporting surface and while travelling across the latter surface, but by the use of the rods 95 embodied in the present invention the balls are caused to bound or jump off the lower reticulated supporting screen surface or mesh and forcefully strike the sifting screen above.

It will be understood that changes in the 100 general dimensions of the improved cleaning means for sifting screens as hereinbefore described may be adopted and the size of the mesh modified at will without departing from the spirit of the invention.

What is claimed as new is:

1. A sifting means comprising a frame with dividing partitions extending transversely the full width thereof at distances apart, an upper sifting screen, a lower supporting screen surface having larger mesh than the said sifting screen, the two screens with the frame and partitions forming enclosed compartments, rods extending across the compartments in contact with and ex- 125
- 130

tending slightly above the lower screen surface, and resilient balls mounted in the compartments for free movement and contact with and over the rods to quickly and effectively cause a bounding action of the balls when the frame and screens are subjected to vibratory motion for cleaning the meshes of the upper sifting screen.

2. A sifting means of the class specified, comprising a sieve-like box, an upper sifting screen forming a top covering for the box, a lower coarser mesh supporting screen providing a bottom for the box, transverse partitions extending fully across the width of the box at intervals, continuous transverse projections bearing upon and extending slightly above the lower supporting screen between the partitions and the ends of the box, and resilient balls disposed and freely movable in the spaces between the partitions and the latter and the ends of the box and having contact with and movable over the said projections to cause the balls to quickly and forcefully bound in different directions against the top sifting screen to maintain the latter in unclogged condition.

3. A sifting means of the class specified, comprising a box structure having a top sifting screen and a bottom supporting screen secured thereto, the bottom supporting screen being of coarser mesh than the sifting screen, a plurality of partitions extending fully transversely across the box and forming a plurality of compartments, projecting means between the partitions and the latter and the ends of the box and continuing fully across and in close relation to the lower supporting screen terminally secured to the side members of the box and extending slightly above the surface of the

latter screen, the partitions having parallel sides, and resilient balls in the compartments and freely movable on the supporting screen and over the projecting means and rendered forcefully active and given a bounding operation in different directions by contact with the said means between the partitions and the ends of the box to strike the upper sifting screen and maintain the meshes of the latter free of clogging material.

4. A sifting means of the class specified, comprising a box-like frame having an upper sifting screen and a lower supporting screen forming the top and bottom portions of the frame, the lower supporting screen being of coarser mesh than the sifting screen, a plurality of partitions extending fully transversely across the frame at regular distances apart to form compartments between the screens with the sides and ends of the frame, the said partitions having parallel sides and upper reduced edges terminating below the sifting screen to minimize the dimensions of the upper terminals of the partitions adjacent to the screen to render the operation of the latter more sensitive, transversely extending rods in the compartments in close contact with the lower supporting screen and extending slightly above the upper surface of said supporting screen, and resilient balls mounted and freely movable in the compartments and over the rods and having unrestricted and forceful bounding action to strike the upper sifting screen and keep the latter free from clogging.

In testimony whereof I have hereunto set my hand.

CHANDOS ROY DIMM.
